UNITED STATES PATENT OFFICE.

HUGH A. PERRY AND JAMES MILINARE, OF CHICAGO, ILLINOIS.

DISPENSING DEVICE.

Application filed December 2, 1925. Serial No. 72,734.

Our invention relates to bank slip dispensing devices and has for its primary objects the provision of a dispensing device of this character embodying such novel features of construction whereby plates containing advertising matter may be removably mounted thereon; the provision of a novel frictional means for holding the slips in a position so that they may be readily withdrawn by a bank customer but which prevents such freedom of movement of the slips as to create a waste of same by the unpremeditated withdrawal of more than one slip at a time; and further the invention aims to provide a device of this character which is of very simple, economical and efficient construction.

Other objects and advantages of the invention will be developed in the course of the following description. The various features of novelty which characterize our invention are pointed out with particularity in the claims annexed to and forming a part of this specification. For a better understanding of the invention, however, reference should be had to the accompanying drawing which illustrates the now preferred embodiment of the invention. It is to be understood, however, that we do not propose to limit ourselves to the precise structure shown and described but reserve the right to make such changes and modifications therein as fairly fall within the spirit and scope of the invention as claimed.

In the drawings,

Figure 1 is a perspective view of a device constructed in accordance with our invention and having duplicate dispensing sides; Figure 2 is a fragmentary cross section through one unit of the device shown in Figure 1; Figure 3 is a longitudinal sectional view on the line 3—3 of Figure 2; and Figure 4 is a sectional detail in perspective.

Referring specifically to the drawings, wherein like reference characters denote similar parts in all views, numeral 1 indicates the casing or housing having end walls 3, a bottom wall 2 and a top wall 4. The two sides of the casing are open and receive the glass faced plate 5 which is divided into spaces for advertising matter. The glass plates 5 may be in one piece or in sections as may be deemed most expedient. The end walls 3 have their edges slope inwardly toward the top of the box so as to better display the advertising matter upon the plates 5

which have their edges lie flush with the edges of the end walls 3.

Bordering each marginal edge of the side openings of the box and set inwardly from the plane of the edges of the end walls 3 is a flange 6 which is clearly indicated in Figures 2 and 3. This flange 6 forms a backing for the advertising plate 5.

A glass shelf 7 is disposed at each side of the casing 1 such shelves being supported by plates 8. The plates 8 are removably secured to upward flanges 2^a of the bottom 2 and have end clips 9 for guarding and spacedly supporting the shelves 7 from the plates. Also, each of the backing flanges 6 has an outward bottom ledge 6^a to form a support for the glass faced advertising plates 5, which are encased in frames 5^a, while the inner ends of the lateral clips 9 form an abutment or guard therefor. A cover 10 having an overhanging marginal flange 10^a acts to snugly retain the glass faced advertising plates 5 against the upper portion of the flange 6. When it is desired to move the advertising plate 5 it is only necessary to remove the cover 10 and draw the advertising plates outwardly so that they may be lifted from the pocket formed by the glass shelf 7, its end clips 9 and the flange 6.

Two series of standards 11 are supported by the bottom of the casing in spaced parallel relation the rolls of bank slips to be dispensed are mounted on these standards. A description of one set of standards and the relation of the rolls thereto will suffice as they are exact duplicates. The standards 11 may if desired be mounted upon a base plate 11^a as shown in the drawings, the advantage of this being that the standards can be readily removed. The opposed surfaces of each standard are slotted as indicated at 12 to receive the projecting ends of the pinnacles 13 of the spools 13^a on which is wound the tape or ribbon of paper 14 which is made up of a series of connected slips.

The height of the ledge 6^a of the flange 6 is somewhat above the levels of the bottom flange 2^a and the plate 8 whereby to leave a direct horizontal passage or opening between the interior of the housing and the space beneath the glass shelf 7. The paper 14 is designed to be pulled through this opening. Each of the plates 8 is provided adjacent its outer edge with an opening 16 so that a customer can by the use of his

finger pull the paper 14 outwardly sufficiently so that the end will project through the space between the plates 8 and the shelf 7 and beyond the edge of said shelf so that 5 it may be grasped. The lower outer edge of the glass shelf 7 is squared so that a slip can be brought to bear thereagainst and readily torn off. The roll may be perforated at the junction of two adjacent slips to 10 facilitate the tearing off of a slip.

In order to prevent such free movement of the spool 13^a as to either unroll a plurality of slips as a result of a short pull on the end of the strip or to withdraw the end 15 of the strip from the opening 16 as a result of jarring the casing 1, we have provided weights 17 whose trunnions 17^a ride in the grooves 12. The lower sections of the weights rest upon the roll of strips 14 and 20 this surface is very smooth so as not to tear or otherwise injure the slips. It will be readily appreciated that the use of these weights 17 will prevent any undesired rotation of the spools 13^a and at the same time 25 will not in any way hamper or prevent a customer from readily getting the desired slip.

In replacing or removing the spools 13^a it is only necessary to remove the cover 10 30 and rock the glass faced advertising plate 5 outwardly so that it can be lifted from the pocket formed by the lower part of the flange 6 and the inner edge of the shelf 8 and its clamping pieces 9.

35 Having this described our invention, what we claim as new and desire to secure by Letters Patent is:

1. A dispensing device of the class described comprising a casing having an open-

ing in one side through which the material 40 to be dispensed may be inserted, a closure plate for said opening, supporting means for said plate, a slotted guide projecting from said casing through which the material is 45 designed to be withdrawn, the inner transverse edge of said guide cooperating with said plate-supporting means to define a pocket for one edge of said closure plate and movable means engageable with said closure plate for removably holding it in said 50 pocket.

2. A dispensing device of the class described comprising a casing having an opening 55 in one side through which the material to be dispensed may be inserted, a closure plate for said opening, supporting means for said plate, a rest projecting from one side of said casing, the latter having a slot through which the material may be withdrawn and over said rest, a shelf spacedly 60 supported upon said rest, means for clamping said shelf to said rest, said shelf with said plate supporting means defining a pocket for one edge of said closure plate and movable means cooperable with said closure plate for removably holding it in said 65 pocket.

3. The structure defined in claim 2, and 70 said movable means comprising a cover for said casing having a depending flange, said flange bearing against said closure plate for retaining the same in said pocket and against said supporting means.

In testimony whereof we affix our signatures.

HUGH A. PERRY.
JAMES MILINARE.
